United States Patent Office

Des. 194,279
Patented Dec. 25, 1962

194,279

TEAPOT

Jay Gaston Wein and Marian Mallory Wein, both of 5905 Le Doux Road, Los Angeles, Calif.

Filed Apr. 12, 1962, Ser. No. 69,687

Term of patent 14 years

(Cl. D44—26)

We claim:

The ornamental design for a teapot, substantially as shown.
